SEPARATING AND GRADING MACHINE

Robert E. Thurner, Milwaukee, Wis.

Application December 17, 1940, Serial No. 370,507

2 Claims. (Cl. 209—284)

This invention appertains to machines for grading and separating materials, and more particularly to a novel device for reclaiming contaminated "carburizer."

"Carburizer" is a granular material used in the heat treatment of steel, and during the continued use thereof, the same becomes mixed with dust particles and fine scale, which must be removed if the "carburizer" is to be used again.

One of the primary objects of my invention is to provide a closed machine in which the material to be cleaned is dumped, with means for automatically agitating and carrying the material to one end of the machine and to a suitable receiving receptacle, the dust particles being separated from the material during the agitation of the material.

Another salient object of my invention is the provision of a reticulated or foraminous drum rotatably mounted in the casing, with means for leading the material from a hopper to the low end of the drum, the drum having means for carrying the material from one end thereof to the other during the rotation of the drum, whereby the material will be effectively operated upon.

A further object of my invention is the provision of novel means for supporting and rotating the drum, and for effectively holding the drum against longitudinal shifting movement during the rotation thereof.

A further important object of my invention is the provision of a novel shield arranged at the low end of the drum for guiding the material into the drum from the hopper and for preventing the escape of the material from the low end of the drum, the shield also forming a bearing surface for engaging a thrust roller utilized to hold the drum against longitudinal shifting movement.

A still further object of my invention is the provision of novel means for adjustably mounting the drive motor in the casing, whereby the same can be moved to the best advantage relative to the drum and to the drive and supporting shafts for the drum.

With these and other objects in view, the invention consists in the novel construction, arrangement, and formation of parts, as will be hereinafter more specifically described, claimed, and illustrated in the accompanying drawings, in which drawings:

Figure 1 is a perspective view of my novel machine.

Figure 2 is an enlarged, central, vertical, sectional view through the machine.

Figure 3 is a fragmentary, transverse, sectional view through the machine, taken on the line 3—3 of Figure 2, looking in the direction of the arrows.

Figure 4 is a fragmentary, transverse, sec-

tional view taken on the line 4—4 of Figure 2, looking in the direction of the arrows, illustrating the thrust and guard shield on the lower end of the drum.

5 Figure 5 is a detail, sectional view taken on the line 5—5 of Figure 2, looking in the direction of the arrows, illustrating the drive for the drum.

Figure 6 is a detail, horizontal, sectional view taken on the line 6—6 of Figure 2, looking in the direction of the arrows, illustrating the adjustable support for the motor.

Figure 7 is a detail, sectional view taken on the line 7—7 of Figure 6, looking in the direction of the arrows.

15 Referring to the drawings in detail, wherein similar reference characters designate corresponding parts throughout the several views, the letter A generally indicates my novel machine, and the same includes a casing 10 in which the various parts are mounted.

The casing can be constructed in any desired manner, and, as shown, the same includes corner angle iron standards 11 connected at their upper and lower ends by transversely and longitudinally extending angle iron strips 12. This provides a rigid supporting frame, and, if desired, the frame can be further reinforced by other brace strips 13. Welded or riveted to the frame are sheet metal side walls 14 and sheet metal end walls 15.

20 Arranged within the top of the casing 10 is a hopper 16 for initially receiving the material to be cleaned or separated, and this hopper is provided with a bottom inclined wall 17, which leads down toward a discharge spout 18. Directly below the hopper is a rotatable grading or separating drum 19, and this drum is disposed at an angle to the horizontal, and the spout 18 leads into the lower end of said drum. The drum 19 can be constructed in various manners, and, as shown in

25 the present instance, the same includes solid annular end bands 20 connected to the body portion 21 of the drum, which can be formed from perforated sheet metal or heavy wire screen. Arranged within the drum is a double screw or spiral blade 22, and this double screw serves to reinforce the drum and to carry the material gradually from the lower end of the drum to the high discharge end of the drum.

In order to effectively support and rotate the 30 drum, a pair of spaced, parallel shafts 23 are provided, and these shafts adjacent their opposite ends are provided with rubber friction drive rollers 24, which engage the annular bands 20 of the drum. The shafts 23 are disposed on

35 opposite sides of the longitudinal center of the drum, and the drum rests between the shafts and on the friction rollers 24. Consequently, upon the rotation of the shafts 23, by means which will be later described, the drum can be 40 rotated. The shafts are rotatably mounted in

45

50

suitable front and rear bearings 25 and 26, and these bearings can be supported by transverse brace bars 27, and these bars can be suitably secured to the frame of the machine.

One of the important features of my invention is the provision of an annular plate 28 located at the extreme lower end of the drum, and this plate is rigidly secured to the adjacent annular band 29 of the drum. This plate prevents the downflow of material from the drum and acts as an annular bearing track for an antifriction thrust roller 29. This roller 29 is carried by a bracket 30, which is, in turn, secured to a partition wall 31, which extends transversely across the casing. The thrust roller 29 prevents the downward shifting movement of the drum and holds the drum in place during the rotation thereof. The annular plate 28 carries a frusto-conical shield 32, which serves to control the flow of material from the spout 18 and delivers the same to the interior of the drum during rotation.

Also arranged within the casing below the high end of the drum is a receiving funnel 33, and the material is adapted to be fed from the drum by the screw 22 into said funnel. The funnel terminates in an inclined chute 34, which leads out of the end wall of the casing. In practice, a suitable receptacle can be placed under the chute for catching the material.

The partition wall 31 divides the casing into a motor-receiving chamber 35 and a dust-receiving chamber 36. A sliding drawer 37 is mounted within the dust-receiving chamber 36 below the drum, and the drawer is adapted to receive the dust and fine scale which falls from the drum during the agitation of the material. This drawer 37 can be removed through one side wall 14 of the casing, and the drawer can be provided with a suitable hand pull 38. The casing above the drawer 37 can be provided with an inclined guard flange 39, and this flange extends around the upper edge of the drawer, so as to effectively guide the dust into the drawer and to prevent the seeping of dust into the bottom of the casing.

An electric motor 40 of the desired rating is arranged within the chamber 35, and the armature shaft 41 of the motor has keyed thereto spaced pulley wheels 42 and 43, around which are trained drive pulley belts 44 and 45. These belts are also trained about relatively large pulley wheels 46 and 47, which are keyed or otherwise secured to the shafts 23.

I provide a novel mounting for the motor, whereby the motor can be raised and lowered and shifted back and forth to adjust the tension on the drive belts. The mounting for the motor includes transversely extending channel bars 48, and these channel bars have their ends resting upon brackets 49, which are rigidly secured to the bottom frame beams 12. The brackets 49 are slotted, as at 50, and bolts 51 extend through the bars 48 and the slots in said brackets. Hence, the bars 48 can be adjusted back and forth. The motor 40 is connected by hinges 52 to one of the bars 48, and the other of said bars carries adjustable threaded rods 53, and these rods are, in turn, connected to the base of the motor.

Thus, it is obvious that by adjusting the rods up and down, the motor can be raised and lowered on the hinges, and by shifting the bars 48

back and forth, the motor can be bodily moved longitudinally in the casing. Thus, the motor can be disposed to the best advantage relative to the drum and to the drive shafts. It is also obvious that the pulley wheels 46 and 47 can also be adjusted back and forth on their shafts to a desired position.

In use of my machine, the material to be cleaned or separated is dumped into the hopper 16, and the electric circuit is closed through the motor. The shafts 23 will be turned through the pulley wheels 46 and 47, and the rotation of the shafts will turn the drum through the medium of the friction rollers 24.

The material will flow down the spout 18 onto the flared shield 32, which effectively regulates the supply delivered to the drum. The annular shield plate 28 will prevent the falling of the material from the drum, and the material will gradually be carried up the inclined drum by the feed screw 22, and during the travel of the material up the drum the same will be effectively agitated, permitting the dropping of the fine material through the drum. The coarse clean material will be carried up the top edge of the drum and into the funnel 33, and the material will then be discharged through the spout 34, as previously set forth. The fine material falling from the drum will be caught by the drawer, and the drawer can be readily removed for dumping.

While I have stated that the machine is particularly adapted for cleaning "carburizer," it is to be understood that the machine can be used for various other purposes.

Changes in details may be made without departing from the spirit of the scope of my invention, but what I claim as new is:

1. In a separating and grading machine, a hopper for initially receiving material, an inclined drum rotatably mounted below the hopper having a body portion provided with openings for permitting the passage of fine particles therethrough, a feed screw carried by the interior of said drum for conveying material from the low end of the drum to the high end of the drum, a receiving funnel arranged under the high end of the drum, means for rotating the drum, an annular shield plate carried by the lower end of the drum for preventing discharge of the material from the lower end of the drum, a flared distributing skirt carried by the annular shield plate extending into said drum, and a delivery spout leading from the hopper and extending into the lower end of the drum through the shield plate terminating in close proximity to the distributing skirt for delivering material directly thereon.

2. In a separating or grading machine, a hopper, an inclined drum rotatably mounted below said hopper, a plate secured to the lower end of said drum and provided with a central opening, an inwardly extending frusto-conical shield carried by said plate surrounding said opening, and a delivery spout leading from said hopper into the lower end of the drum through the opening in the plate, said spout terminating in close proximity to the lower end of the frusto-conical shield for delivering material directly thereon, said frusto-conical shield rotating past the discharge end of the delivery spout.

ROBERT E. TURNER.
